UNITED STATES PATENT OFFICE.

HENRY A. WISE WOOD, OF NEW YORK, N. Y., ASSIGNOR, BY MESNE ASSIGNMENTS, TO THE AUTOPLATE COMPANY OF AMERICA, OF JERSEY CITY, NEW JERSEY, A CORPORATION OF NEW JERSEY.

STEAM-TABLE.

1,058,397.

Specification of Letters Patent.

Patented Apr. 8, 1913.

Application filed May 18, 1906, Serial No. 317,457. Renewed September 7, 1912. Serial No. 719,162.

To all whom it may concern:

Be it known that I, HENRY A. WISE Wood, a citizen of the United States, residing at New York, in the county of New York and 5 State of New York, have invented a new and useful Steam-Table, of which the following is a specification.

My invention relates to steam tables for use in drying stereotype matrices; the particular objects being to provide a steam pressure cylinder for operating the table, located beneath the plane of the type and preferably below the bed where it is out of the way; moreover, to provide the steam table with 15 means for performing the function of, and eliminating the ordinary elevating table used in this art; to provide a loading and ejecting device in order to save the necessity of pushing the form in and pulling it out by 20 hand; and in general, to improve the construction of devices of this character in such a manner as to save room, time, and labor during one of the most important operations in the manufacture of stereotypes.

Reference is to be had to the accompanying three sheets of drawings, in which—

Figure 1 is a side elevation partly in section of a steam table showing one way in which the principles of my invention may 30 be embodied. Fig. 2 is an end elevation of the same partly in section. Fig. 3 is a sectional view on the line 3 of Fig. 1. Fig. 4 is an elevation of a portion of a steam table showing a modification. Fig. 5 is an elevation partly in section of another form in which the invention may be embodied. Fig. 6 is an end elevation partly in section showing another form of the invention. Fig. 7 is a side elevation of another form of the 35 device provided with a loading and ejecting device. Fig. 8 is an end elevation of the same. Fig. 9 is a fragmentary plan of part of the loading and ejecting device. Fig. 10 is a side elevation of the same partly in section on an enlarged scale, and Fig. 11 is a plan showing another part of the loading and ejecting device.

Referring first to Figs. 1, 2 and 3, it will be seen that I have shown a frame 10 upon 50 which is mounted a stationary platen 11. Below this platen is arranged a bed or table 12. This table is provided with a flexible tube 13 by means of which steam or other heating fluid may be introduced into it. The table is connected by means of a rod 55

14 with a plunger 15. This plunger works in a power cylinder 16, supplied with steam or other fluid under pressure, through a pipe 17, this pipe in the present instance acting both for supply and exhaust. The cylinder 60 is mounted in the present instance, in stationary position on the frame, and the plunger works back and forth and raises the steam table with the form thereon toward the stationary platen or press-head so that 65 the matrix can be put under pressure while being dried by the heat of the table. The frame may be provided with guides 18 for directing the motion of the table. Ordinarily, if the floor of the stereotyping room 70 is uneven, or if for any reason the level of the steam table is different from that of the iron tables on which the forms are placed in the composing room, it is necessary to use lifting tables to receive the form from the 75 iron tables and transfer it to the steam table, the lifting table being adjusted by a screw to the level of one and then to that of the other. In order to obviate the necessity of using such lifting tables, I have provided the 80 steam table with an extension 19. In the form illustrated in these figures, this extension is fixed to the steam table and moves vertically with it. This extension is preferably provided with a depending rod 20 having 85 flexible connections 21 passing over pulleys 22 to support a counter-weight 23, or it may be counterbalanced in any other way. The extension, it will be seen, is of such a nature that its upper surface is always at 90 the same elevation as the upper surface of the steam table or bed. When the tables from the composing room are brought in, any difference in level may be avoided by 95 simply turning a steam cock and moving the steam-table and extension up or down.

Relative motion between the bed and platen or press-head, heating of the steam table, application of pressure and manipulation of the extension 19 can be secured in 100 many other ways than that which I have described with reference to Figs. 1, 2 and 3. Two other forms which I have provided for accomplishing certain of these results are shown in Figs. 4 and 5. In the former, an extension 190 is shown as being ordinarily 105 stationary, but adapted to have the same elevation as the top of the steam table when the latter is lowered to its lowest position. In Fig. 5, I have shown an extension 191 110

provided with means for raising and lowering it independently of the steam table. In this case a cylinder 25 is formed either on the frame of the machine or independently of it, and a piston 26 therein operates the extension 191 through a piston rod 27. A supply and exhaust pipe 28 is shown for the usual purpose.

Another form in which my invention can 10 more conveniently be embodied is shown in Fig. 6. In this case the steam table is provided with a hollow plunger 150 having an opening 151 communicating with an elongated cavity 152. The cylinder 160 is provided with a steam pipe 161, and during the reciprocation of the steam table this pipe communicates constantly with the elongated cavity 152 so that steam is supplied to the interior of the steam table constantly without the use of the flexible connection which is employed in the form shown in Fig. 1. The exhaust steam and drippings from the steam table pass down through a tube 120 to the bottom of the cavity within the hollow plunger. A port 121 communicates with an elongated cavity 122 in the outside of the plunger, which in turn communicates with the exhaust pipe 162. In a manner similar to that mentioned above, this exhaust pipe 20 is always in communication with the cavity 122, and consequently the heating of the steam table and the removal of exhaust steam therefrom can be constantly carried on. In this form, the extension 19 shown in Fig. 1, 30 may, if desired, be employed, and it may be provided with a loading and ejecting device, but I have shown this device as applied to the form shown in Figs. 7 and 8, in which the platen 110 is mounted on sliding rods 40 111 which are counterbalanced by springs 112 and are connected by a head 113. This head is operated by a plunger 114 in a steam cylinder 115, the table or bed being stationary.

45 The loading and ejecting device comprises the following elements: A rod 30 is connected with the platen and rises and falls with it. This rod is provided with a rack 31 which meshes with a pinion 32 mounted on 50 a shaft 33. This shaft carries arms 34 which are connected with links 36. These links are provided with slots 37 at their ends for receiving a cross-rod 38. The cross-rod carries a bar 39, which, as shown in Fig. 10, 55 is preferably of triangular or trapezoidal shape and fits in a groove 40 in the extension 19, the groove being of substantially the same shape as the bar to enable the bar to drop into the groove and bring the top 60 surface of the bar flush with the top of the extension, and to allow no small apertures into which loose type might drop. When the platen is in its highest position, the bar 39 will remain in the groove 40, but as it descends toward the table, the movement of

the rod 30 will cause the links 36 to move the cross-rod 38 along the extension 19, as is indicated in dotted lines in Fig. 10.

It will be seen that the swinging of the links 36 in an upward direction at their outer ends not only tends to pull the bars 39 along the extension, but raises them out of the groove in opposition to the counterbalanced weight.

The cross-bar is yieldingly connected with 75 the links by means of a pair of springs 41 in the slots 37. The cross-rod also carries a frame 42 having a pin 43 projecting inwardly from each side toward the extension and adapted to engage a form thereon.

Stop pins 44 on the extension 19 are provided for the purpose of arresting the motion of the carriage when it has brought the form under the platen. This device is preferably counterbalanced by a weight 45 or 80 the like, connected by cords or other flexible connections 46 with the bar 39. These cords pass over pulleys 47 at the rear of the bar when it is in its extreme position. The operation of this part of the device will be 85 readily understood. As the platen descends from its highest position, the rack 31 operates the pinion to force the carriage or frame connected with the cross-rod 38 into the press. Most of the motion of the carriage 90 takes place before the platen is in such position as to exert any pressure. After the chase is placed in proper position on the steam table, it is of course necessary that further downward motion of the platen 95 should take place, therefore, when the chase reaches this position and the rod is stopped by the pins 44, the additional motion of the links 36 will be taken up by the springs 41, the chase remaining stationary. During the 100 compressing operation, there will, of course, be no motion of the form with respect to the steam table, and when the platen first starts back, there is sufficient lost-motion between the ends of the chase and the pins 105 43, which engage it at this time, to prevent the chase from being moved before the pressure is taken off. The remaining motion of the platen in an upward direction withdraws the carriage, the pins 43 engaging the 110 rear of the chase and ejecting it from the press.

While I have illustrated and described certain forms in which my invention may be embodied, it is to be understood that 115 many modifications may be made in each of them, and the invention can be carried out in many ways within the scope thereof as expressed in the claims. Therefore, I do not wish to be limited to any or all of the 120 particular forms shown, but

What I do claim and desire to secure by Letters Patent is:—

1. In a power steam table for drying stereotype matrices, the combination of a 125 130

- bed, a platen, means for heating said steam table, a steam cylinder located beneath the platen and having means for causing a relative motion between the bed and the platen, 5 and a movable extension for the bed. 2. In a press for drying stereotype matrices, the combination of a steam-heated bed and a platen, means for causing a relative motion between the bed and platen located 10 beneath the platen, and an extension for the bed for receiving forms and delivering them to the bed, the top of said extension being of the same elevation as the top of the bed. 3. In a press for drying stereotype matrices, the combination of a hollow bed, 15 means for introducing a heating medium into said bed, an extension for the bed located at the same elevation as the bed, and means independent of the bed for counterbalancing said extension. 4. In a press for drying stereotype matrices, the combination of a bed, a movable extension for the bed located at the same elevation as the bed and connected 20 with the bed, and means independent of the bed for constantly maintaining the extension level and at the same elevation as the bed. 5. In a press for drying stereotype matrices, the combination of a bed, means for 25 heating said bed, means for moving said bed, an extension for the bed, and means independent of the bed for counterbalancing the extension. 35 6. In a press for drying stereotype matrices, the combination of a bed for receiving chases, an extension for the bed, means for keeping the extension level, a loading and ejecting device connected with the said 40 extension, and means for operating said device. 7. In a press for drying stereotype matrices, the combination of a bed for receiving chases, means for heating said bed, a 45 platen, means located beneath the plane of the platen for causing a relative motion between the bed and platen, and means for moving chases operable by said first named means. 50 8. In a steam table for drying stereotype matrices, the combination of a hollow bed for receiving the form, means for conducting steam into said bed for heating it, a platen, and means for delivering the form 55 to drying position. 9. In a press for drying stereotype matrices, the combination with a bed adapted to receive a form, of means for introducing a heating medium into the bed, and means 60 for ejecting the form from the press. 10. In a steam table, the combination of a bed, a platen, means located beneath the plane of the type for causing a relative motion between the bed and platen, means 65 for delivering chases to the bed and remov- ing them therefrom, and means connected with the first named means for operating said chase-moving means to deliver a chase while the bed and platen move relatively toward each other and for ejecting the chase 70 when the bed and platen move relatively away from each other. 11. In a press, the combination of a bed, a platen, means located beneath the platen for causing a relative motion between the 75 bed and platen, means for delivering chases to the bed and removing them therefrom, and means connected with the first named means for operating said chase-moving means to deliver a chase while the bed and platen move relatively toward each other. 80 12. In a press, the combination of a bed, a platen, means located beneath the platen for causing a relative motion between the bed and platen, means for delivering chases to the bed and removing them therefrom, and means connected with the first named means for ejecting a chase when the bed and platen move relatively away from each other. 85 90 13. The combination of a stereotype drying device, an extension therefor, said stereotype drying device having a movable compressing element, means for moving said element, and a chase-moving means comprising a frame movable along said extension, and means connected with said means for operating the movable element of the drying device for reciprocating said frame. 95 14. The combination with a drying press 100 having a movable compressing element, of a loading device comprising a frame, and means operated by the motion of said compressing element yieldingly connected with said frame for moving it toward the press. 105 15. The combination with a drying device 110 for stereotype matrices, of a loading device comprising a frame, means yieldingly connected with said frame for moving it toward said drying device, means for limiting the motion of the frame with respect to the drying device, and a yielding connection adapted to move after the motion of the frame is arrested. 16. The combination with a drying device 115 for stereotype matrices, of a loading device comprising a frame, means yieldingly connected with said frame for moving it toward said drying device, and a yielding connection adapted to move after the motion of the frame is arrested. 120 17. The combination with a drying press 125 having a movable compressing element, of a loading device comprising a frame, means yieldingly connected with said frame for moving it toward the press, means for limiting the motion of the frame with respect to the press, and a yielding connection adapted to move after the motion of the frame is arrested. 130

18. The combination of a drying device having a movable compressing element, a loading device and means for moving the loading device into the press while the compressing element is operating, said means being operated by the motion of said compressing element, and means for permitting the continued motion of the compressing element to take place after the loading device has entered the press without continuing the motion of the loading device. 40
19. The combination of a press having a movable element, a movable frame, means connected with said movable element for moving the frame when the movable element moves, and means for preventing the motion of the movable element from being transmitted to the frame near the end of the travel of the movable element. 45
20. The combination with a press of a loading and unloading device comprising a frame, a support for said frame, a bar connected with said frame and extending across the support, a link for moving said bar, and a yielding connection between the link and bar. 50
21. The combination with a press of a loading and unloading device comprising a frame, a bar connected with said frame, a link for moving said bar, and a yielding connection between the link and bar. 55
22. The combination with a support provided with a transverse groove, of a loading and unloading device comprising a frame having a bar fitting in said groove, and means for moving said frame along the support. 60
23. The combination with a press having an extension provided with a transverse groove, of a loading and unloading device comprising a frame having a bar fitting in said groove, means for moving said frame along the extension, and a yielding connection between the frame and the moving means. 65
24. The combination with a drying press having a movable compressing element, of a loading device comprising a frame, and means operated by the motion of said compressing element for moving said loading device toward the press. 70
25. The combination with a stereotype matrix drying press having an extension, and means for heating said press, of a loading and ejecting device comprising means positively controlled by the motion of the press for moving forms along said extension toward and from the press. 75
26. The combination with a stereotype matrix drying press, and means for heating said press, of a loading and ejecting device, and means operated by the press for automatically and positively moving forms toward and from the press. 80
27. The combination with a stereotype matrix drying press, and means for heating said press, of a form loading and ejecting device therefor comprising means automatically operated by the press for moving a form into the press when the press-platen and bed relatively approach each other. 85
- In testimony whereof I have hereunto set my hand, in the presence of two subscribing witnesses.
